UNITED STATES PATENT OFFICE.

ARTHUR T. GOLDSBOROUGH, OF WASHINGTON, DISTRICT OF COLUMBIA.

BENCH-PLANE.

SPECIFICATION forming part of Letters Patent No. 293,864, dated February 19, 1884.

Application filed July 19, 1883. (No model.)

To all whom it may concern:

Be it known that I, ARTHUR T. GOLDSBOROUGH, a resident of the city of Washington and District of Columbia, have invented certain new and useful Improvements in Metallic Bench-Planes, of which the following is a specification.

The nature of this invention relates to improvements in metallic bench-planes; and it consists in certain novel details of construction and arrangement, the particulars of which will be hereinafter fully described.

In the accompanying drawings, Figure 1 is a longitudinal section, in elevation, of a plane illustrating my invention. Fig. 2 is a plan view of the stock and handle, a portion of the upper part being broken away. Fig. 3 is a section in elevation on the line 3 3 of Fig. 1. Fig. 4 is an inverted plan view on the line 4 4 of Fig. 1. Fig. 5 is a detail view of a portion of the bit and its adjusting-screw.

Similar letters denote like parts.

A represents the stock, and B represents a bridge or portion connecting the sides, in which moves the main or adjusting screw C. The bridge in this case, being only apertured to carry the said screw and not slotted for the insertion of the bit, may be made smaller and thinner than heretofore, and yet be possessed of the requisite strength and rigidity. Under the bridge, and in close proximity thereto, are two small short cleats or studs, *bb*, and directly above the throat H is located another cleat or stud, *b'*, both sets being arranged in the same line with respect to the throat of the plane. The bit D is formed with a T-shaped slot at its upper end, and the adjusting-screw C is provided with a corresponding head, which is T-shaped in cross-section. When in position, the bit may be moved freely up and down between the cleats by means of the said screw. The bit is inserted from below through the throat of the plane, as shown in dotted lines, Fig. 1, and some means must be provided for allowing sufficient movement of the said bit for it to be placed over the head of its adjusting-screw. This may be accomplished in several ways—as, for instance, forming the bit of a width less than that of the stock between the upper and lower set of

cleats, or making one of the upper sets of cleats removable, or by forming triangular recesses E in the stock, within which recesses the upper end of the bit can be raised out of the path of the main or adjusting screw sufficiently to allow it, when only partially inserted, to be placed over its head. The motion of the screw is then reversed and the bit drawn in between the upper set of cleats as far as may be desired. I prefer the latter plan, as it allows the use of a somewhat wider bit in proportion to the thickness of the sides of the stock, unless, as in the first-mentioned method, they (the sides) be made very thin. The bit, having been inserted loosely, is secured in position as follows: At a point about midway between the bridge and throat, and attached to the inside of the sole of the stock, is located the supplemental bridge F, in which is mounted the set-screw G, which has a conical or wedge-like end, *g*. The said bridge and screw are preferably placed at such an angle that the point of the screw G will strike the inside of the sole and the under side of the bit at equal angles, so that the force exerted by it, when tightened so as to lock the previously-adjusted bit, will be evenly distributed between the parts with which it is in contact. The rear portion of the stock is provided with the inwardly-extending ribs *LL*, the inner sides of which being oblique, they form together an inverted-V-shaped groove or slot.

The handle I is preferably made of cast-iron. It is provided with the internal-screw-threaded boss J and set-screw *i*, and the foot *I'*, which has extending or spreading sides *KK*. When the foot of said handle is inserted endwise into the V-shaped groove and the set-screw tightened against the sole of the stock, the handle will be securely held. By loosening the said screw *i*, the handle can be readily removed, and the said screw is intended to be arranged for operation by hand or with a screw-driver, as most convenient.

Having described my invention, I claim—

1. A bench-plane having a single bit and a detachably-connected adjusting-screw arranged in line therewith, and adapted to move said bit longitudinally in its plane of adjustment, a stock provided with rigidly-fixed in-

ward projections arranged on parallel lines on each side thereof, between which the bit is held and moved, and means for locking the adjusted bit by forcing it obliquely upward 5 against the projections of the stock, as set forth.

2. A bench-plane having a single bit, an adjusting-screw detachably connected thereto, a stock formed with spaces or recesses leading 10 obliquely upward from the throat and adapted to allow the upper end of said bit to be moved at right angles to its plane of adjustment while being connected to its adjusting-screw, and a set-screw arranged to exert pressure below 15 said bit and lock it in its adjusted position.

3. In a bench plane, a stock formed with a bridge connecting the sides thereof on the line of the cutting-bit, and adapted to support a screw for controlling the longitudinal adjustment thereof, and a supplementary bridge lo- 20

cated below the bit and adapted to support a set-screw operating between the bit and the inner side of the sole, cleats projecting inwardly from the sides of said stock, between which said bit moves and is adjusted, and a 25 recess or space between the lower and upper cleats, within which the bit may be moved at right angles to its plane of adjustment, as set forth.

4. The stock A, formed with bridges B and 30 F, the cleats b and b', and recesses E or equivalent, substantially as shown and described.

In testimony whereof I have hereunto subscribed my name this 19th day of July, A. D. 1883.

ARTHUR T. GOLDSBOROUGH.
